UNITED STATES PATENT OFFICE.

MICHAEL J. HANNAN, OF MARIETTA, OHIO.

WELL-BORING DRILL.

Application filed January 7, 1925. Serial No. 1,026.

To all whom it may concern:

Be it known that I, MICHAEL J. HANNAN, a citizen of the United States, residing at Marietta, in the county of Washington and 5 State of Ohio, have invented certain new and useful Improvements in Well-Boring Drills, of which the following is a specification, reference being had therein to the accompanying drawing.

10 This invention has relation to drills for boring oil, gas and other wells, and has for its object to provide means, constituting part of the drilling bit, for kneading or stirring up the earth, sand or loam, cut out and 15 loosened by the bit, with the water supplied to the well during the boring operations, so as to reduce the earthy material to the consistency of soft mud, which will not impede the drilling operations, and which will facilitate 20 the removal of the bit from the well at intervals as the work progresses, with the accumulated débris.

A further object of the invention is the provision of means for maintaining the bit 25 in a central, upright position, at the bottom of the well, when the connecting rods or shaft sections are detached, so that the latter may be readily recoupled to the bit thus avoiding the difficulty occasioned, as is often 30 the case, by the tilting of the bit in the well, and the displacement from a central, accessible position of the threaded pin or boss, by which the lower section of the connecting rod is attached to the bit.

35 With the above stated, special object in view, my invention consists of a drilling bit having the features of construction and arrangement hereinafter particularly described and claimed.

40 In the accompanying drawing Figure 1 is a face view of a drill bit embodying my invention, positioned in a well.

Figure 2 is a similar edge view.

45 Figure 3 an upper end view of the drill, and

Figure 4 is a perspective view of the upper part of the bit.

1, designates a drilling bit comprising the flattened lower part 2 preferably grooved 50 or channeled on its flattened surfaces, and formed with a suitable lower cutting, chisel-like edge.

Above the flattened portion 2 the drill is contracted to form a shank 3, preferably 55 flattened on opposite sides to coincide with the flattened sides of the part 2.

Above the shank 3, the drill is further contracted to form a neck 5, which terminates with the usual conical screw threaded connecting end part 6. The neck is recessed on 60 opposite sides to form shoulders 8, for the engagement of a grab, in case the bit becomes disconnected from the drill rods.

The special feature constituting my invention consists of the laterally projecting lugs 65 7, 7, formed as a part of and extending radially from the flattened sides of the shank 3, and which run or project crosswise of or at right angles to the planes of the flattened sides of the part 3, and above the channels 70 or grooves.

The drill is made of oblong shape in cross section and channeled in its flattened faces, so as to facilitate the lateral cutting operations of the drill and provide clearance 75 spaces for the passage of the material removed from the sides of the well.

The lugs 7, 7, project to a distance, between their outer ends, substantially equal to the width of the flattened portion of the 80 bit, so as to reach the walls of the well, and, while the drill is being rotated, to thoroughly knead and mix the accumulated moistened débris, and prevent it from becoming impacted around the drill. 85

As the lugs 7, 7, project to an extent equal to the greater width of the bit, the latter will be therefore supported at all times in an upright position, by the contact of the ends of the lugs with the walls of the well, and hence the upper section or stem of the bit will be easily accessible for the purpose of attaching thereto the connecting rod or shaft through which the drill is operated, or for the engagement of a "grab" as above 95 mentioned, with the shouldered part of the neck of the stem.

I claim:

1. A well boring drill, consisting of a flattened and vertically channeled bit with a contracted shank rising therefrom and provided with means for connection to a drill rod, said shank having a pair of radially attached projecting lugs formed thereon below the upper end of the shank 100 above the bit and at right angles to the flattened sides of the bit, said lugs being free at their outer ends and extending substantially the width of the bit and arranged 105 and adapted to thoroughly stir and mix together the particles of earthy material bored and separated by the bit. 110

2. A well boring drill, consisting of a bit and a shank, provided with separable means for attachment to a drill rod, the bit being of oblong shape in cross section and the shank provided with horizontally projected free ended lugs located below its upper end and above the body of the bit and extending substantially the width of the bit, said lugs being adapted to stir and mix the material removed by the bit during the drilling operation and to maintain the bit in a central upright position, when the drilling rod is disconnected. 5 25
3. A well boring drill, having a bit of oblong shape in cross section, with a stem which is detachable from the drill rod, and provided with stirrers or beaters, located above the bit and below the upper end of the shank, said beaters being disposed cross- wise of the flattened sides of the bit, and forming an integral part thereof, said lugs 10 20 29 35
- being arranged and adapted to loosen, stir and mix the material cut by the bit and tending to lodge in the space around the shank of the bit, and said lugs being free and disconnected at their outer ends and extended substantially the width of the bit.
4. A well boring drill, consisting of a longitudinally channeled bit of oblong shape in cross section, with a contracted shank, adapted for attachment to and detachment from the drill rod and having laterally projecting lugs formed thereon and located at right angles to the sides of the bit, and below the upper end of the shank, the outer ends of said lugs being free and disconnected, so as to constitute beaters or stirrers of the earthy material cut by the drill, and the stem formed with recesses and shoulders, above the said lugs for the attachment of a grab. 30

MICHAEL J. HANNAN.
